UNITED STATES PATENT OFFICE.

HOMER E. FROST, OF CLEVELAND, OHIO, ASSIGNOR TO THE ELECTRIC CONTROLLER & MANUFACTURING COMPANY, OF CLEVELAND, OHIO, A CORPORATION OF OHIO.

OVERLOAD DEVICE.

Application filed August 1, 1921. Serial No. 488,990.

To all whom it may concern:

Be it known that I, HOMER E. FROST, a citizen of the United States, residing at Cleveland, in the county of Cuyahoga and State of Ohio, have invented new and useful Improvements in Overload Devices, of which the following is a specification.

My invention relates to overload devices for electric motors, and more particularly for alternating current motor systems which have overload devices with a heat-expansive wire in each of two of the phases in 2-phase or 3-phase systems. If the overload device is designed to be tripped by the action of separate springs for balancing the pulls of the expansive wires, the operation of the overload device by a single phase current in one wire (the other wire being inoperative for any reason) requires considerably more current than when the operation of the overload device is caused by the expansive action of both wires. It is the object of this invention to provide means whereby such an overload device as described may be tripped by the employment of a single spring or by the application of spring tension at a single point without the disadvantages attending the use of a separate spring for each expansion wire. The objects of this invention will be better understood in connection with the following description.

On the accompanying drawings, Fig. 1 is a side elevation of an overload device embodying the principles of my invention; Fig. 2, a bottom plan view of Fig. 1 with some of the parts omitted; Fig. 3, a view of the upper part of Fig. 1; Fig. 4, a sectional detail showing the rear member of the tripping device; Fig. 5, an enlarged detail looking at the right hand end of Fig. 3; Fig. 6, a detail of the tripping mechanism in the position in which it is when the circuit is open; Fig. 7, a diagrammatic view of the circuits which may accompany my device; and Fig. 8, a diagram showing the efficiency of my invention.

On the drawings 1 indicates an insulating base composed of slate, for example. 2 and 3 are heat-expansive wires severally connected at one end to the metal blocks 6 and 7 slidably seated in the respective forks

4 and 5, and adjustably held therein by the nuts 8 and 9 which bear on the outer edges of the forks. The remaining ends of the wires 2 and 3 are respectively connected to the ends of the operating levers 10 and 11, both pivoted on the pin or pivot 12 supported by the base 1. Each lever is composed of an outer member 13 and an inner member 14 connected together at their upper ends by a pin 15. To the pins 15 the wires 2 and 3 are respectively attached. The levers 10 and 11 have inwardly projecting tripping fingers 16 and 17, respectively, formed by projections from their members 13 and 14. The projections of each pair of members are connected together by a spacing pin 18. The members 13 of the levers have below the projections 16 and 17 holes to loosely receive the end necks 19 of the equalizing pin or bar 20, which has central between the necks 19 the neck 21 to which one end of the operating spring 22 is attached, the other end thereof being connected to the post 23 secured to the base 1.

24 is a switch-tripping lever comprising the back member 25 and the front member 26, both pivoted on the pivot 27 secured to the base 1. The members are connected together by the pin 28. The lower end of the member 25 is engaged by the spacing pin 18 of the lever 11, and the lower end of the lever member 26 is engaged by the spacing pin 18 of the lever 10, as shown best in Fig. 5. A switch-reset spring 29 tends to keep the lower ends of the members 25 and 26 in contact with the fingers 16 and 17. The upper end of the member 25 has the fork members 30 and 31, between which is the fixed post 32 acting as a stop for the fork members and as a support for the bellcrank lever 33 pivoted on the outer end thereof, and having the arms 34 and 35. An overthrow spring 36 connects the arm 34 to the upper end of the member 26, the spring lying to the right of the pivot post 32 when the arm 35 is horizontal. The arm 35 is connected by the link 36' of insulating material to the free end of the lever 37 carried by the pivot 38 below the link. The pivot 39, which connects the link to the lever 38, also carries the rocking

contact 40, having its upper end arranged to engage the fixed contact or post 41 when the link and the arm (which are toggle-members) are in a substantially straight line, as shown on Fig. 1. The lower end of the lever is connected to the spring 42 which allows the contact 40 to have a wiping action on the contact 41. The contact 41 is connected by the lead 43 to the terminal 44, 10 and the pivot 38 is connected by the lead 45 to the terminal 46.

The ends of the expansive wire 2 are connected by the wires 47 and 48 to the secondary winding 53 of the transformer 49, 15 and the ends of the expansive wire 3 are connected by the wires 50 and 51 to the secondary winding 54 of the transformer 52. The primary winding 55 of the transformer 49 has the terminals 56 and 57, and 20 the primary winding 58 of the transformer 52 has the terminals 59 and 60. 61 and 62 represent the cores of the transformers.

Referring now to Fig. 7, the terminals 56 and 59 are connected to the two terminals 63 and 64 of the alternating current motor 65. The terminals 57 and 60 are connected to the movable switch members 66 and 67 of the switch 68. The third motor terminal 69 is connected to the movable switch member 70. The said switch members are pivotally connected to the operating bar 71, actuated by the switch-operating winding 72 to close the switch members 66, 67 and 70 on their fixed contacts 73, 74 and 75, and actuated by the spring 76 to open the said switch members when the winding 72 is de-energized. The contacts 73, 74 and 75 are connected to the source of alternating current supply by 40 the supply wires 77, 78 and 79. The winding 72 is connected in the circuit of the neutral contact 75 and in one of the outer wires, as 77, through the hand switch 80 and the parts 37, 38, 40 and 41, as shown in Fig. 7.

On Fig. 8 the equalizer 27 is represented as applied directly to the wires 2 and 3 at the points *a* and *b*, these indicating the position of the equalizer when the wires 2 and 3 are cold. The corresponding point of application of the spring 22 is indicated by the letter *c*. *a'* and *b'* indicate the position of the equalizer 27 when both the wires 2 and 3 become heated and stretch 55 equally under the pull of the spring 22 until the levers 10 and 11 jointly cause the tripping lever 24 to open the contacts 40 and 41. When the equalizer 27 takes the position *a'-b'*, the point of application of the spring 22 is at *c'*. If the circuit of one of the wires, as 2, has been interrupted, the equalizer will take the diagonal position *a-b'*, the point of application of the spring 22 being at *c'*.

Let it be assumed that the spring 22 exerts a pull of 15 lbs. at the point *c*. Then the pull thereof on the points *a* and *b* will be 7.5 lbs. each. Assume that, when the equalizer is at the position *a-b'*, the pull of the spring has been reduced to 6 lbs. Then the pull at *a'* and *b'* will be reduced to 3 lbs. each. If the wire 2 is out of circuit, the point *a* will remain stationary while the point *b* will move to *b'*, the point *c* moving to *c''*, at which point the spring exerts a pull of only 10.5 lbs. divided between the points *a* and *b'*. The pull at *b'* will be somewhat in excess of 5.25 lbs., owing to the movement of the point *c''* of the application of the spring 22 slightly toward the point *b'*. The necks of the equalizer bar 27 cause a readjustment of the points of application when the bar moves from the position *a-b* to the diagonal position *a-b'*, so that the power of the spring on the point *b'* is greater than on the point *a*. Thus, the spring which exerts a pull of only 3 lbs. on each wire when both wires are equally heated, exerts a pull of more than 5.25 lbs. on one heated wire, as 3, when the other wire, as 2, is open circuited. This means that the heated wire 3 is stretched sufficiently to trip the switch contact 40 before the wire 3 is heated to such a high temperature as would have been required if both wires were heated equally. If separate springs were employed, each pulling 7.5 lbs. at the points *a* and *b*, and the wire 2 was out of circuit, the spring acting on the point *a* would still exert a pull of 7.5 lbs. while the spring acting on the point *b'* would exert a pull of 3 lbs., a loss of 2.25 lbs. over the pull exerted at the point *b'* when only one spring is pulling at the point *c'*.

Referring particularly to Fig. 7, if the switch 80 is closed, the single phase current in the winding 72 will cause the switches 66, 67 and 70 to engage the contacts 73, 74 and 75, thereby connecting the neutral wire 79 to the motor terminal 69, while the outer wires 77 and 78 are connected to the remaining motor terminals 63 and 64 through the primary windings of the transformers 49 and 52. When the contacts 40 and 41 are opened, the winding 72 is de-energized, permitting the spring 76 to open the switches 66, 67 and 70 and cause the motor 65 to stop. As the upper end of the lever 24 is moved to the left in Fig. 1 by the action of the lever 10 or the lever 11 or both, the spring 36 passes from the right side of the fulcrum 32 of the lever 33 to the left side thereof, thereby causing the latter to move quickly from the position shown in Fig. 1 to that shown in Fig. 6 where the toggle-members 35, 36', have pulled the lever 37 to the left enough to open the contacts 40 and 41.

I have shown my invention in connection

with a three-wire alternating current system, but it is evident that it is applicable to other multiphase systems.

By varying the gradient of the spring 22, 5 it is possible to vary the relative amounts of current required for single and multiphase operations.

I claim—

1. In an overload device for alternating 10 current systems, two expansive wires, one in each of two phases, an overload switch controlling the opening of the circuit of the wires, and means for tripping the switch when either or both of the wires expand a 15 predetermined distance, but with less consumption of current when one wire is open circuited.

2. In an overload device for alternating 20 current systems, two expansive wires, one in each of two phases, an overload switch controlling the opening of the circuit of the wires, and means including a single spring for tripping the switch when either or both of the wires expand a predetermined dis- 25 tance, but with less consumption of current when one wire is open circuited.

3. In an overload device for alternating 30 current systems, two expansive wires, one in each of two phases, an equalizer bar, means loosely connecting its ends to the wires, a spring connected to the central portion of the bar and operating to move the bar as one or both wires expand, and an overload switch controlling the opening of the cir- 35 cuit of the wires and tripped by the move-

ment of either or both ends of the bar a predetermined distance during the expansion of one or both wires.

4. In an overload device for alternating 40 current systems, two expansive wires, one in each of two phases, a lever having one end attached to an end of one wire, a lever having one end attached to an end of the other wire, an equalizer bar arranged transversely 45 of the levers and having its ends loosely connected to the remaining ends of the levers, a spring connected to the central portion of the bar and operating to move the bar as one or both wires expand, and an overload switch controlling the opening of the circuit 50 of the wires and tripped by the movement of either or both ends of the bar a predetermined distance during the expansion of one or both wires.

5. In an overload device for alternating 55 current systems, two expansive wires, one in each of two phases, an equalizer bar having end and central necks, means loosely connecting the end necks with the wires, a spring connected to the central neck and operating to move the bar as one or both 60 wires expand, and an overload switch controlling the opening of the circuit of the wires and tripped by the movement of either or both ends of the bar a predetermined dis- 65 tance during the expansion of one or both wires.

Signed at Cleveland, Ohio, this 29th day of July, 1921.

HOMER E. FROST.
